SHEET FEEDING DEVICE

Albert W. Metzner, Dayton, Ohio, assignor to The Standard Register Company, Dayton, Ohio, a corporation of Ohio

Application August 18, 1941, Serial No. 407,317

16 Claims. (Cl. 197—130)

This invention pertains to writing and imprinting machines and more particularly to record material feeding and aligning means therefor.

Modern commercial practice has necessitated rapid production of typewritten and imprinted records. Power operated automatic recording machines, wherein the writing operation is controlled by punched cards, tapes or by remote control from a distant master apparatus, have become quite common. Such machines usually employ continuous series connected detachable form stationery. However, there are certain fields and conditions of use wherein use of cut sheets or independent sets of forms having interleaved transfer sheets are preferable. For such use, it is desirable that the sheets be automatically advanced into writing position and properly aligned in timed sequence with the operation of the machine.

The present sheet feeding apparatus embodies means for automatically delivering separate record sheets or units comprising sets of plural sheets from a supply magazine in continuous success and momentarily arresting the released sheets or sets thereof in properly aligned relation in an advanced position preparatory to their admission to the writing or imprinting machine in synchronism with successive impression imparting operations thereof.

The object of the present invention is to improve the construction, as well as the means and mode of operation of sheet feeding and aligning mechanism for writing and imprinting machines, whereby such devices may not only be economically manufactured and installed, but will be efficient in use, automatic in operation, uniform in action, having relatively few operating parts, and be unlikely to get out of repair.

A further object of the invention is to enable record sheets or sets of sheets to be fed seriatim from a source of supply and presented in aligned and registering relation with the imprinting devices in continuous timed sequence synchronized with the operation of the writing or imprinting apparatus.

A further object of the invention is to provide automatically operated sheet ejector means by which sheets or sets thereof are discharged one at a time from a supply magazine thereof and presented in predetermined relation with the writing or imprinting apparatus.

A further object of the invention is to provide sheet timing means and a trip means therefor by which presentation of the record sheet in

impression receiving position is in synchronism with the operation of the imprinting means.

A further object of the invention is to provide an intermittently operated sheet feeding mechanism and actuating means for driving the sheet feeding mechanism in timed sequence with a writing or imprinting apparatus.

5 A further object of the invention is to provide a sheet feeding apparatus for writing or imprinting machines possessing the advantageous structural features and inherent meritorious characteristics and mode of operation herein mentioned.

10 With the above primary and other incidental objects in view as will more fully appear in the specification, the invention intended to be protected by Letters Patent consists of the features of construction, the parts and combinations thereof, and the mode of operation, or their equivalents, as hereinafter described or illustrated in the accompanying drawings.

15 In the drawings, wherein is shown the preferred but obviously not necessarily the only form of embodiment of the invention,

20 Fig. 1 is a perspective view of a portion of a writing or imprinting machine and a sheet feeding and aligning mechanism embodying the present invention applied thereto.

25 Fig. 2 is a front elevation of the sheet feeding apparatus, including the platen roll of a writing machine.

30 Fig. 3 is a side elevation of the assembled mechanism showing a record sheet in process of being inscribed and the sheet ejector about to discharge a succeeding sheet from the magazine.

35 Fig. 4 is a similar side elevation of the apparatus in a succeeding stage of operation, wherein the succeeding record sheet has been released from the magazine and arrested in timing position as the trailing edge of the preceding sheet is being advanced into impression receiving position.

40 Fig. 5 illustrates a further stage of the sheet advancing operation, wherein the momentarily arrested sheet is being released for advancement in immediately following relation with the preceding sheet.

45 Fig. 6 is a vertical sectional view on line 6—6 of Fig. 2, illustrating the tandem frictional drive devices.

50 Fig. 7 is a detail view of the gear drive mechanism for feeding sheets of greater length.

55 Fig. 8 is a detail view of the sheet arresting and timing device.

Like parts are indicated by similar characters of reference throughout the several views.

The present sheet feeding and aligning device is adapted to be mounted in cooperative relation upon a typewriter, tabulator, billing machine or other writing or imprinting mechanism, which, preferably but not necessarily, embody a revolvable platen roll. The apparatus is not limited, however, to such mechanisms, but may be adapted for operation with flat bed type recording or business machines, including conventional addressing machines and the like.

In the drawings, 1 is the platen carriage of a recording machine, of which 2 is the rotary platen roll having at its opposite ends knobs 3 by which it may be manually actuated. The platen roll is further equipped with the customary variable 4, by which the platen may be adjusted independently of the line spacing and other driving means to enable accurate registry of predetermined lines or areas of the record sheets with the imprinting position, and a ratchet wheel 5 on the platen roll shaft forming part of a line spacing mechanism.

In usual commercial installations, such machines are power driven and are controlled by punched record cards, a punched tape or other legend determining device. They may, however, be manually operated, in which event the platen roll is actuated through a line spacing mechanism as is common in typewriting machines. In either event, the platen roll shaft carries a gear 6 rotating in unison with the platen roll, by which motion is transmitted to the sheet feeding mechanism.

The frame of the present record machine attachment includes relatively spaced end plates 7—1 detachably mounted upon the platen carriage 1 and supporting therebetween an upwardly and rearwardly inclined sheet magazine 8 comprising the back wall 8' and side walls 9 together with a bottom 10 fixedly connected with each other and with the end plates 7. At the front margin of the magazine bottom 10 is an upstanding flange or retainer lip 11. Adjustably secured to the back wall 8' of the magazine are relatively spaced angle bars 12 adjustable toward and from each other within the limits of slots 13 to agree with the width of a packet of sheets 14 to be fed, which are positioned therebetween. The magazine is provided with a false spring 15 urged back against which the supply pack 16 rests, and which pushes the supply pack of sheets forwardly against the upstanding retainer flange 11 as succeeding sheets are removed from the front thereof. The sheets of the pack are loosely confined at the top of the magazine by a transverse rod 11'.

Journalized in the end plates 7 in parallel spaced relation with the platen roll 2 are rotary shafts 16 and 17, which are rotated in unison with the platen roll by a gear train, wherein the gear 6 on the platen roll shaft intermeshes with an idler pinion 18 mounted on the end plate 7, which in turn engages a gear 19 on the shaft 16 to drive such shaft in the same direction of rotation as the platen roller. The gear 19 in turn drives a gear 20 on the shaft 17 to rotate the latter in reverse direction. Mounted on the shaft 17 for to and fro axial adjustment into different planes of rotation are ejector fingers 21, of which there may be one or more. The ejector fingers 21 are secured in adjusted position on the shaft by thumb screws 22. The ejectors are provided with rubber or other tenacious terminals 23, and

are of sufficient length that upon rotation of the shaft 17 the heads or terminals 23 will frictionally engage the foremost record sheet in the magazine and lift the sheet upwardly until its lower margin clears the retainer flange 11. As the ejector continues to rotate upwardly, the displaced sheet 14' is released and drops by gravity in front of the magazine, which has a dependent guide portion 24 which is substantially aligned with the conventional paper guide 25 of the platen carriage. At the same time, the pack of sheets within the magazine is urged forwardly against the limiting flange 11 by the spring pressed back against which the pack rests, thereby maintaining the foremost sheet of the pack in constant relation with the path of travel of the frictional ejector 21—23.

Fig. 3 illustrates the ejector at the moment it is in engagement with the record sheet to be discharged.

In Fig. 4 the parts are shown advanced slightly beyond the initial engaging position shown in Fig. 3, and the ejector finger 21 having lifted the foremost sheet of the pack over the flange 11, has released the sheet 14' which has then fallen vertically in front of the magazine and the continuing guide 24 until arrested by a stop bar 26. The stop bar 26 extends across the machine and is supported at its opposite ends upon reciprocatory slides 27 located beneath the magazine or pack holder 8 and opposite the transverse shaft 16. The slides 27 are slotted at 28 through which extend supporting studs 29 upon which the slides are movable to and fro. Each slide 27 is formed with a hanger bracket 30 to which the opposite ends of the stop bar 26 are adjustably attached by set screws 31 engageable through slots 32. The slides 27 and with them the stop bar 26 are spring retracted in a forward direction by tractile springs 33 attached at one end to studs 34 carried by the slides and at its opposite end to dependent portions of the magazine or pack holder 8. Interconnecting the reciprocatory slides 27 is a transverse shaft 35 which carries small friction rollers 36. At the forward limit of sliding motion of the slides 27, the rollers 36 engage and cooperate with larger friction wheels 37 carried by the transverse shaft 16. The slides 27 and with them the stop bar 26 and friction rollers 36 are retracted in timed sequence with other operative motions by cams 38 on opposite ends of the transverse shaft 16, which at each rotation thereof engage projections 39 on the reciprocatory slides 27 to retract the latter against the yielding resistance of the springs 33.

At the moment the ejected sheet 14' is released by the ejector fingers 21 and allowed to drop, the reciprocatory slides 27 and the stop bar 26 are in retracted position, and the nose or projection 39 of the slides are riding upon the high segments of the cams 38. The released sheet 14' is therefore arrested by the engagement of its lower margin with the stop bar, and is illustrated in Fig. 4. At this moment, the preceding ejected sheet 14' has not yet been advanced sufficiently far about the platen roll to permit the sheet 14' to immediately follow. The upper end of the preceding ejected sheet is then behind the stop bar 26 in overlapping relation with the succeeding sheet, as also shown in Fig. 4. The high segment of the cam 38 is of sufficient extent to so hold the stop bar 26 retracted until the trailing margin of the preceding sheet is advanced even with the stop bar and forward edge of the succeeding sheet. The high segments of the cams 38 passing

beyond the noses 39 of the slides 27 permit the latter to advance until the rollers 36 engage the ejected sheet and press it against the friction wheels 37, as is illustrated in Fig. 5. At the same moment and by the same movement the stop bar 26 is advanced from under the lower margin of the ejected sheet, and the further rotation of the shaft 16 causes the sheet to be fed downwardly by the coaction of the rollers 36 and friction wheels 37 until the forward portion of the sheet is frictionally engaged between the friction rollers 40 and the platen roll 2 by which advancement of the sheet is continued past the writing position at the front of the platen roll, indicated by the type bar 41, as shown in Fig. 6. Temporarily the sheet will be under the combined feeding influence of the rollers 36 and friction wheels 37 and the rollers 40 and platen roll 2, as in Figs. 3 and 6. However, as the sheet is advanced the cams 38 completing their rotation again retract the slides 27 and return the stop bar 26 into the path of the next descending ejected sheet, preparatory to repetition of the cycle of operation.

Beyond the platen roll the inscribed portions of the successive sheets are advanced upwardly through a chute 41 which comprises two inter pivoted, relatively spaced, parallel plates 42 and 43, which are adjustably carried by an arm 44 journaled on the shaft 17. To insure proper direction of the sheets into the chute and to maintain the advancement thereof until the trailing margin has passed into the chute, an additional friction roller 45 cooperates with the top of the platen roll, beyond the writing position, to exert final feeding influence upon the successive sheets

In the event that longer lengths of record material are to be fed, the gear ratio of the driving train is changed, as shown in Fig. 7, to enable more than one turn of the platen roll between the ejection of succeeding sheets. As there shown, the initial driving gear 6' upon the platen roll shaft is of smaller diameter and is inversely proportionate to the length of the sheets to be fed. Consequently, the shafts 16 and 17 are rotated at reduced speed and the ejector finger is caused to engage once with each sheet of increased length and the rollers 36 and wheels 37 are delayed in their impinging action upon the advanced sheet until the preceding sheet has been advanced even therewith.

The sequence of operation includes the ejection of the sheets one by one from the magazine by lifting the foremost sheet upward over the detent flange 11 by frictional engagement of the ejector arm 21, the rotation of which is timed in relation with the subsequent feeding devices proportionate to the length of the sheet. The sheet is deposited substantially upright upon the stop bar 26. There are two sets of sheet feeding devices, to wit, the intermittently operable friction rollers 36 and wheels 37, and the more or less continuously operative friction rollers 40 which cooperate with the platen roller 2 to advance the record material as the writing of each line of matter is completed. The successive sheets are advanced in close succession, so that the leading edge of one sheet follows closely the trailing edge of the preceding sheet. The automatic withdrawal of the stop bar 26 in timed sequence with the operation of the feeding devices serves to time the advancement of each sheet in close relation. The stop bar is retracted into the path of the ejected sheet preparatory to temporarily arresting such sheet before the trailing edge of the preceding sheet has

been advanced past such point. When the trailing edge of the sheet being fed about the platen reaches the plane of the stop bar 26, the latter is withdrawn to release the arrested succeeding sheet. Simultaneously therewith the intermittent preliminary frictional feeding members 36-37 engage the released strip to advance it into engaging relation with platen engaging frictional rollers 40. Continued advancement of the sheet 10 is maintained as each written line is completed, by the frictional rollers 40 and finally by the rollers 45 until the sheet is advanced beyond the platen roll into the chute 41 or into a suitable receiving compartment.

15 In order that the sheets may be accurately aligned transversely with the writing position, flaring guides 46 are adjustably mounted on the guide or apron 24 below the magazine. The released sheet drops in front of the guide or apron 20 24 between the flaring guides 46 by which it is deflected laterally in one direction or the other as may be necessary to present it in properly aligned relation. In initially adjusting the device 25 for feeding particular printed forms, the customary variable is employed to adjust the platen roll independently of the feeding mechanism to bring the writing lines or spaces into accurate registry with the writing or imprinting position. Then the stop bar 26 is vertically adjusted by 30 loosening the set screws 31 to present the bottom edge of the succeeding sheet in proper relation with the trailing edge of the preceding edge at the moment that the stop bar 26 is withdrawn to release the sheet. After being once set in agreement with particular printed forms to be fed by 35 adjusting the platen roll variable and the stop bar, the sequence of operation and timing of succeeding sheets is maintained automatically until other forms having differently positioned writing lines are to be employed, which then necessitates 40 readjustment.

Where herein the term sheet is employed to identify succeeding record receiving units to be fed, it is to be understood that there is contemplated not only the advancement of single sheets, but also record units which comprise plural sheets which may be interconnected in sets or books, with or without interleaved carbon or transfer material. Furthermore, while only frictional feeding means is illustrated for ejecting 45 and subsequently advancing the succeeding record units, it is to be understood that positive pin type feeding means, of which sundry forms are well known in this art, may be utilized in lieu 50 of frictional means.

From the above description it will be apparent 55 that there is thus provided a device of the character described possessing the particular features of advantage before enumerated as desirable, but which obviously is susceptible of modification in its form, proportions, detail construction and arrangement of parts without departing from the principle involved or sacrificing any of its advantages.

65 While in order to comply with the statute, the invention has been described in language more or less specific as to structural features, it is to be understood that the invention is not limited to the specific features shown, but that the means 70 and construction herein disclosed comprise the preferred form of several modes of putting the invention into effect, and the invention is therefore claimed in any of its forms or modifications within the legitimate and valid scope of the appended claims.

Having thus described my invention, I claim:

1. In a writing or imprinting machine having a platen roll about which record material is advanced past an impression receiving position, a sheet feeding mechanism therefor including a magazine for a packet of separate sheets, a stop against which the packet of sheets is pressed to position, each succeeding sheet of the pack in a common plane as the preceding sheet is ejected therefrom, a frictional sheet ejector operative to elevate the foremost sheet of the packet out of engaged relation within the magazine and thereafter release the sheet for descent in a substantially upright position, a sheet detent in the path of the descending sheet for temporarily arresting the descent thereof, frictional rollers intermittently operable to engage the arrested sheet, means for withdrawing the sheet detent and effecting engagement of the sheet by the frictional rollers to advance the sheet into cooperative relation with the platen roll, feeding means for advancing the sheet about the platen roll, and motion transmitting means actuated by rotation of the platen roll for operating the ejector, withdrawing the sheet detent, operatively engaging the friction rollers in timed sequence with the advancement of a preceding sheet about the platen roll.

2. In a writing or imprinting machine, wherein record material is progressively advanced about a platen roll past an impression receiving position, a magazine for a packet of separate record material sheets, a pair of rotary shafts disposed in parallel spaced relation with the platen roll and with each other, one of said shafts being disposed adjacent to the record material magazine, a frictional ejector member carried by the latter shaft and intermittently engageable with the foremost sheet in the magazine with an upward wiping movement by which the sheet is dislodged from the magazine and subsequently released for descent in substantially upright position, friction wheels carried by the other of said rotary shafts, a reciprocating slide actuated by rotation of the latter shaft, a sheet detent and a frictional roller carried by the slide and alternately engageable with the descended sheet by reciprocation of the slide, a cam on said shaft controlling the reciprocation of the slide and motion transmitting means actuated in timed relation with the rotation of the platen roll for effecting alternation of said slide in timed sequence with the operation of the ejector and rotation of the platen roll.

3. In a writing or imprinting machine having a platen roll about which record material is advanced past an impression receiving position, a sheet feeding mechanism therefor including a magazine for supporting a packet of separate sheets in a substantially upright position, a sheet ejector comprising a rotary arm having wiping engagement with the foremost sheet of the packet in an upward direction to dislodge the sheet from the packet and adapted to release the sheet for descent in a substantially upright position, a reciprocating detent for arresting the descending sheet, detent retracting means and motion transmitting means for effecting rotation of the ejector arm and retraction of the reciprocating detent in timed sequence with the rotation of the platen roll.

4. In a writing or imprinting machine, wherein record material is progressively advanced about a platen roll and past an impression receiving position, a magazine for a packet of separate record receiving units from which said units are

ejected one by one, a frictional ejector engageable with the foremost record unit of the packet and operative to initially elevate the engaged unit relative to the packet and subsequently release the ejected unit for descent in a substantially upright position, record unit detent device and feeding means and a record unit feeding device alternately engageable with the record unit and motion transmitting means actuated by rotation of the platen for operating the ejector to release a record unit from the magazine and present the detent in the path of the released record unit and thereafter withdraw the detent and engage the arrested unit by the feeding device to present the record unit in operative relation with the platen roll in timed sequence with the rotation thereof.

5. In a writing or imprinting machine, wherein record material is advanced about a platen roll and past an impression receiving position, a sheet feeding mechanism including a magazine to receive a packet of separate sheets, a stop against which the foremost sheet of the packet is pressed, pressure means for urging the packet of sheets against said stop, a traveling ejector having frictional engagement in an upward direction with the foremost sheet of the packet and operative to lift said sheet over the stop, and subsequently release the ejected sheet for descent in substantially upright position, a detent operative in timed relation with the ejector for temporarily arresting the ejected sheet, a sheet feeding device for advancing the sheet about the platen roll and means for timing the ejection of the sheet and the engagement of the sheet feeding device with the sheet in accordance with the rotation of the platen roll.

6. In a writing and imprinting machine, wherein record material is progressively advanced about a platen roll and past an impression receiving position, a magazine wherein a supply packet of separate sheets are received in a substantially upright position, a traveling ejector having intermittent upwardly wiping engagement with succeeding foremost sheets of the supply packet to eject the engaged foremost sheet from the magazine and subsequently releasing the sheet for descent in a substantially upright relation into overlapping relation with a preceding ejected sheet, a detent for temporarily arresting the ejected sheet until the overlapped portion of the preceding sheet has been advanced therebeyond.

7. In a writing or imprinting machine, wherein record material is progressively advanced about a platen roll and past an impression receiving position, a sheet feeding mechanism including a magazine supporting a packet of separate sheets in substantially upright position, a rotary ejector having frictional upwardly wiping contact with succeeding foremost sheets of the packet whereby succeeding sheets are removed therefrom and operative to lift the foremost sheet from the packet substantially in the plane thereof and subsequently release the ejected sheet for descent in a substantially vertical position, separate relatively spaced sheet detent and auxiliary sheet feeding devices in advance spaced relation with the platen roll in engaging relation with which the released sheet is temporarily arrested, and actuating means therefor operative in timed relation with the actuation of the platen roll operative to disengage the detent and engage the auxiliary strip feeding device for advancing the sheet into operative relation with

the platen roll and actuating means for the ejector operated by rotation of the platen roll.

8. In a writing or imprinting machine, wherein record material is progressively advanced about a platen roll and past an impression receiving position, a pack holder for supporting a supply packet of separate sheets in substantially upright position, an ejector having upward frictional wiping engagement with the foremost sheet of the supply packet and operative to initially raise the sheet out of its relation with the remaining sheet and subsequently release the sheet for descent in a substantially upright position into overlapping relation with the trailing portion of the preceding released sheet, a detent for temporarily arresting the succeeding sheet while permitting the relative advancement of the overlapped portion of the preceding released sheet into feeding engagement with the platen roll, pressure means for urging the foremost sheet of the packet into the range of operation of the ejector, and actuating means for the ejector operated by rotation of the platen roll in timed sequence therewith.

9. In a writing or imprinting machine, wherein record material is progressively advanced about a platen roll and past an impression receiving position, an ejector for releasing a succession of sheets one by one from a supply packet and depositing the sheets in substantially upright relation, a sheet detent member and a sheet feeding device interconnected for alternating engagement with a deposited sheet, to initially arrest the sheet and subsequently advance the sheet relative to the platen roll, and actuating means operated by rotation of the platen roll for alternating the engagement of the detent and feeding device with the deposited sheet in synchronism with the rotation of the platen roll.

10. In a writing or imprinting machine, wherein record material is progressively advanced about a platen roll and past an impression receiving position, an ejector for releasing a succession of sheets one by one from a supply packet and depositing the sheets in substantially upright overlapping relation, sheet feeding means for successively advancing the sheets about the platen roll, a detent for arresting each deposited sheet until the trailing edge of the preceding sheet has been advanced at least even with the leading edge of the succeeding sheet, and actuating means operated by rotation of the platen roll for disengaging the detent and releasing the arrested sheet in synchronism with the rotation thereof.

11. In a writing or imprinting machine, wherein record material is progressively advanced about a platen roll and past an impression receiving position, including a sheet feeding mechanism including an ejector for advancing a succession of sheets one by one from a supply packet thereof, a vibratory carrier, a sheet detent carried thereby and movable into and out of the path of ejected sheets to temporarily arrest said sheets, and a sheet feeding device also carried by said vibratory carrier and actuated into engagement with the sheet in alternation with the sheet detent, and actuating means for vibrating the carrier in timed relation with the rotation of the platen roll to disengage the detent from the sheet and engage the feeding device therewith.

12. In a writing or imprinting machine, wherein record material is progressively ad-

vanced about a platen roll and past an impression receiving position, including a sheet feeding mechanism including an ejector for advancing a succession of sheets one by one from a supply packet thereof, a sheet detent movable into and out of engaging relation with the advanced sheet to temporarily arrest said sheet, a sheet feeding device movable into and out of engaging relation with the advanced sheet to further advance the sheet upon disengagement of the detent therefrom, and actuating means controlled by rotation of the platen roll for alternating the engagement of the detent and the feeding device with the advanced sheet in synchronism with the rotation of the platen roll.

13. In a sheet feeding apparatus for a writing or imprinting machine having a platen roll about which the sheets are successively advanced past a record receiving position, a pack holder in which a packet of sheets are supported in substantially upright position, an ejector automatically actuated in timed sequence with the rotation of the platen roll for imparting to the foremost sheet of the packet an upwardly lifting movement substantially in the plane of the sheet, the sheet being thereupon released for descent by gravity, a detent for temporarily arresting the released sheet in overlapping relation with the trailing portion of a previously released sheet being advanced about the platen roll, and means for automatically disengaging the detent in timed sequence with the advancement of the preceding sheet to permit the continued advancement of the temporarily arrested sheet into feeding relation with the platen roll.

14. In a sheet feeding apparatus for a writing or imprinting machine having a platen roll about which the sheets are successively advanced past a record receiving position, a pack holder in which a packet of sheets are supported in substantially upright position, a rotary ejector arm having intermittent frictional wiping engagement in an upwardly direction with the foremost sheet of the packet, by which the sheet is automatically initially lifted upwardly substantially in the plane of the sheet and subsequently released for descent by gravity into overlapping relation with the trailing portion of a preceding released sheet being advanced about the platen roll, and timing means for automatically retarding the advancement of the released sheet until the overlapped trailing edge of the preceding sheet has advanced therebeyond and for releasing the arrested sheet in timed sequence with the advancement of the preceding sheet for further advancement into feeding relation with the platen roll, and sheet feeding means engageable therewith for automatically advancing the sheet about the platen roll and past the record receiving position in timed sequence with the ejection of the sheet from the packet.

15. In a sheet feeding apparatus for a writing machine having a platen roll about which the sheets are successively advanced past a record receiving position, a reciprocatory slide movable into and out of the path of advancement of the sheet to temporarily arrest succeeding sheets, an auxiliary feeding device carried by the slide in spaced relation with the platen roll and movable into engaging relation with each advanced sheet by retraction of the slide from engagement therewith to advance the previously arrested sheet into operative relation with the platen roll, and actuating means for reciprocating the slide in

timed sequence with the rotation of the platen roll.

16. A sheet feeding apparatus for a writing machine having a platen roll about which succeeding sheets are fed past a record receiving position, a magazine wherein a packet of sheets is supported in substantially upright position, a rotary shaft in parallel spaced relation with the platen roll, and rotating in unison therewith but in reverse direction, an ejector arm carried thereby having frictional upwardly wiping contact with the foremost sheet of the supply packet and operative to initially lift the foremost sheet therefrom and release it for descent in a substantially upright position, a rotary shaft interposed in parallel spaced relation intermediate the platen roll and the aforementioned ejector arm shaft, friction discs carried by said intermediate shaft and rotating in unison with the platen roll

and in the same direction, a reciprocating slide member movable into and out of the path of descent of the released sheet and operative to arrest the sheet prior to its operative engagement with the platen roll, friction rollers carried by the slide and movable into and out of cooperative relation with the friction discs upon the intermediate shaft to operatively engage the advanced sheet therebetween, frictional feed rollers cooperative with the platen for advancing each succeeding sheet thereabout, a cam on the intermediate shaft controlling the to and fro movement of the slide to alternate the arresting engagement of the slide and feeding engagement of the friction rollers therewith, and drive means for actuating the respective shafts in unison with the rotation of the platen roll.

ALBERT W. METZNER.
